UNITED STATES PATENT OFFICE

EDWIN CHARLES KUBLER, OF NEW YORK, N. Y.

FOLDING BOX

Application filed March 18, 1927. Serial No. 176,537.

The present invention relates to an improved form of folding box for the storage, shipping and display of articles of all kinds especially pencils.

5 The main object of the invention is to provide a simple, compact, rugged box, made of a minimum number of parts which are integrally connected together so that the whole box can be stamped out in one piece and in 10 one operation.

A further object is to provide a box blank in one piece which can be quickly and easily assembled so that it will stand alone to display the contained articles, while, at the same 15 time, it may be folded into a small space, when not in use, for purposes of shipping and storage.

Further and more specific objects, features, and advantages will more clearly appear 20 from the detailed description given below taken in connection with the accompanying drawings which form part of the specification and which illustrate one embodiment of the invention.

25 The invention is illustrated in a preferred form in the accompanying drawings, wherein Figure 1 is a perspective view of the box as standing for display, Figure 2 is a similar view from behind, showing the box partly 30 unfolded, Figure 3 is a vertical sectional view of the box as folded for shipping, Figure 4 is a view of the box-forming blank entirely unfolded and laid flat, and Figure 5 is a horizontal sectional view of the box as folded for 35 shipping.

Referring to Figure 4, it will be seen that, in the preferred form shown, the blank from which the box is formed comprises a plurality of rectangular sections, together with certain tapering auxiliary flaps hereinafter described. These are separated by scored or weakened portions to facilitate folding, as is well known in this art.

At 10 is shown the front section, which is 40 preferably provided with one or more large openings 11, to permit a view of the contents of the box when used for display.

This section 10 is flanked on each side by side sections 12, outside of these on either 45 side are the two back sections 13 and 14.

The section 14 has a slot 15 and the section 13 has a suitably formed tongue 16, which may be introduced into the slot 15 to lock the parts together, when they have been brought into the position shown in Figure 2. 55

The bottom ends of the side sections are preferably supplied with tapering tabs 17.

At the bottom of the front section 10 is joined the bottom section 18, and beyond this are found the back lining section 19, the supporting section 20 and the spacing element, preferably comprising the three spacing sections 21, 22 and 23. 60

The blank thus far described can be folded to form a securely locked open-topped box 65 without the use of glue or cement, as follows.

Sections 18 to 23 are folded away from the observer in Figure 4 along the scored line between 10 and 18, until the bottom section 18 is at right angles to 10, and the lining 70 section 19 is brought parallel to 10.

The tabs 17, being folded on the dotted lines until they lie against the inside of the sections 12, these sections and the back sections are folded back around the lining section 19 into the position shown in Figure 2, when the tongue 16 and slot 15 may be interlocked as shown in Figure 3. With the section 19 flat against the back sections 13 and 14, as in Figure 3, the tabs 17 are folded flat 75 down on the bottom section 18, as in Figure 5.

The box is now complete. If it is to be used for storage or shipping the sections 20, 21, 22 and 23 are folded flat against the back 80 as in Figures 3 and 5.

If used for display purposes, the extreme section 23 is tucked in between the bottom of the lining section 19 and the back sections 13 and 14, as shown in Figure 3, while the folding sections 21 and 22 are extended so as to bring the supporting section 20 into an inclined position, to support the box in the position shown in Figure 1. 85

While I have described my improvement in detail and with respect to a preferred form thereof, I do not desire to be limited to such details or form since many changes and modifications may be made and the invention embodied in other forms without departing from the spirit and scope of the 90 100

invention in its broader aspects. Hence I desire to cover all modifications and forms coming within the language or scope of any one or more of the appended claims.

5 What I claim is—

1. A foldable one-piece blank for forming a shipping and display box comprising a front section, back sections associated therewith on opposite sides and adapted to interlock when disposed in operative position, a lining section associated with one edge of the front section and adapted to lie in front of the back sections when they are folded into position, and a supporting section connected to the opposite end of the lining section and adapted to lie against the rear face of the back sections when not in use.
  2. A foldable one-piece blank for forming a shipping and display box comprising a front section, side sections foldably connected thereto on opposite sides, back sections foldably connected to the side sections and adapted to interlock when engaged, a bottom section foldably connected to one edge of the front section, and a lining section foldably connected to the bottom section and adapted to lie in front of the back sections when they are in engaged position.
  3. A foldable one-piece blank for forming a shipping and display box comprising a front section, side sections foldably connected thereto on opposite sides, back sections foldably connected to the side sections and adapted to interlock when engaged, a bottom section foldably connected to one edge of the front section, a lining section foldably connected to the bottom section and adapted to lie in front of the back sections when they are in engaged position, and a supporting section foldably connected to the opposite end of the lining section and adapted to lie against the rear of the back sections when not in use.
  4. A foldable one-piece blank for forming a shipping and display box comprising a front section, side sections foldably connected thereto on opposite sides, back sections foldably connected to the side sections and adapted to interlock when engaged, a bottom section foldably connected to one edge of and form a hole at 8, as shown in Figure 5, connected to the bottom section and adapted to lie in front of the back sections when they are in engaged position, a supporting section foldably connected to the opposite end of the lining section and adapted to lie against the rear of the back sections when not in use, and a plurality of spacing sections connected at one end to the lining section and foldable between the back sections and the lining section when not in use, one end of the spacing sections detachably engaged with the lower end of the back sections.
  5. A foldable one-piece blank for forming a shipping and display box comprising a

front section, side sections foldably connected thereto on opposite sides, back sections foldably connected to the side sections and adapted to interlock when engaged, a bottom section foldably connected to one edge of the front section, a lining section foldably connected to the bottom section and adapted to lie in front of the back sections when they are in engaged position, a supporting section foldably connected to the opposite end of the lining section and adapted to lie against the rear of the back sections when not in use, and a plurality of spacing sections connected to one end of the lining section and foldable between the back sections and the lining section when not in use, one of the spacing sections adapted to be tucked in between the lining section and the bottom of the interlocked back sections.

In testimony whereof I have hereto affixed 85
my signature on this 4th day of March 1927.

EDWIN CHARLES KUBLER.
